CLAIM

The ornamental design for a spray dispenser, as shown and described.

DESCRIPTION

FIG. 1 is a bottom perspective view of a spray dispenser showing my new design;

FIG. 2 is a top perspective view of the spray dispenser of FIG. 1;

FIG. 3 is a right side elevational view of the spray dispenser of FIG. 1, the left side view being a mirror image of the right side;

FIG. 4 is a front elevational view of the spray dispenser of FIG. 1;

FIG. 5 is a back elevational view of the spray dispenser of FIG. 1;

FIG. 6 is a top plan view of the spray dispenser of FIG. 1; and,

FIG. 7 is a bottom plan view of the spray dispenser of FIG. 1.

The dashed lines in FIG. 7 showing the internal structure of the spray dispenser depict environmental subject matter only and form no part of the claimed design.
